FUEL INJECTION PUMP

Herbert C. Edwards, Massillon, Ohio, assignor to
 The Timken Roller Bearing Company, Canton,
 Ohio, a corporation of Ohio

Application March 25, 1936, Serial No. 70,804

6 Claims. (CL. 103—41)

This invention relates to fuel injection pumps of the kind having a plurality of reciprocating pistons that are rotated in their respective cylinders by means of a single rack to regulate the quantity of fuel delivered. The invention has for its principal objects to provide the piston-turning rack with means for independently adjusting the angular position of each piston so as to obtain a proper initial setting thereof, to provide a simple stop mechanism for said rack that can be readily adjusted to limit the maximum quantity of fuel delivered, and to provide for simplicity and cheapness of construction and compactness of design. The invention consists in the construction, combinations and arrangements of parts hereinafter described and claimed. In the accompanying drawings, which form part of this specification and wherein like symbols refer to like parts wherever they occur,

20 Fig. 1 is a side elevation of an injection pump embodying my invention,

Fig. 2 is a horizontal section on the line 2—2 in Fig. 1,

Fig. 3 is a section similar to Fig. 2 on an enlarged scale,

Fig. 4 is a vertical transverse section through the pump, the section being taken through one of the pump cylinders on the line 4—4 in Fig. 1,

Fig. 5 is a section similar to Fig. 4, the section being taken through the lower portion of the cylinder at right angles to the section shown in Fig. 4,

Fig. 6 is a longitudinal section through the control rod stop mechanism on the line 6—6 in Fig. 3,

Fig. 7 is a transverse section on the line 7—7 in Fig. 3,

Fig. 8 is a side elevation of the control rod; and

40 Fig. 9 is a cross-section through said rod on the line 9—9 in Fig. 8.

In the accompanying drawings, my invention is shown in connection with a multi-cylinder fuel injection pump comprising a suitable housing 1 provided with a plurality of vertical bores 2 that are spaced apart longitudinally of said housing and have enlarged lower end portions adapted to slidably receive tappet cups 3 that are engaged at their lower ends by cams or tappets 4 on a cam shaft 5 located in the longitudinal chamber 6 in the bottom of the pump housing. Mounted in each of the vertical bores 2 in the pump housing 1 is a pump cylinder 7, which contains a piston and plunger 8 and has an enlarged upper end portion 9 that is held down on an annular seat 10 provided therefor in the upper portion of said bore

by means of a tubular member 11. The member rests on the upper end of the pump cylinder 7 and is provided at its upper end with a seat for a suitable fuel discharge valve 12. Threaded into the upper end of the bore 2 is a tubular fitting 5 or shell 13, which holds the valve seat member 11 down on the upper end of the pump cylinder and is provided at its upper end with a space for a coil spring 14 that normally holds the fuel discharge valve 12 against the seat provided therefor at the upper end of said member. A fuel discharge pipe 15 has a conical end portion seated in a beveled seat provided therefor in the upper end of the tubular fitting or shell 13 and is held in position by means of a cap 16 threaded on the 15 upper end of said fitting.

The pump housing is provided on one side of the cylinders therein with a longitudinal passageway 17, which receives liquid fuel from a suitable feed pump (not shown) and communicates with 20 an inlet port 18 in the wall of each cylinder. Said housing is also provided on the opposite side of said cylinders with a longitudinal overflow passageway 19 that communicates with an overflow port 20 located in each cylinder opposite 25 the inlet port 18 therein. Each piston 8 is of the general type provided with an annular groove 21 that communicates through a longitudinal peripheral groove 22 with the pressure space 23 above the piston and has an inclined or helical 30 upper edge 24, whereby the effective delivery stroke of the piston may be regulated by turning the piston in its cylinder to vary the point in the delivery stroke of the piston in which the overflow port 20 is placed in communication with said pressure space through the grooves 21 and 22. By this arrangement, delivery of the fuel begins 35 as soon as the piston on its way up covers the ports 17 and 18 and ends as soon as the helical upper edge 24 of the annular groove 21 in the 40 piston opens the overflow or by-pass port 20 and relieves the pressure in the space above said piston.

The mechanism for turning the pistons on their axes to vary the amount of fuel delivered 45 thereby comprises axially aligned upper and lower driving and driven sleeves 25 and 26 mounted on the lower end portions of the cylinders and pistons, respectively, and a rack rod 27 mounted in a horizontal bore 28 that extends longitudinally 50 of the pump housing from end to end thereof on one side of the cylinders and cooperates with gears 29 on the upper ends of the driving sleeves. The upper or driving sleeve 25 for each piston is rotatably mounted on the lower end of the cyl- 55

inder therefor; and the lower or driven sleeve 26 has a non-rotatable connection with the lower end of said piston comprising a flat sided portion 30 on the piston that fits a similarly shaped opening in the lower end of said lower sleeve. The driving connection between the driving sleeve 25 and the driven sleeve 26 preferably comprises upwardly extending diametrically opposed tongues 31 on the driven sleeve that fit within 5 downwardly opening diametrically opposed notches 32 provided therefor in the driving sleeve, thereby permitting relative axial movement of the two sleeves, but preventing relative rotary movement thereof.

15 Surrounding the driving and driven sleeves 25 and 26 for each piston is a helical compression spring 33 that serves to retract said piston and to hold the driving sleeve upwardly in the tappet cup receiving portion of the vertical bore in the 20 pump housing. The tappet cup 3 surrounds the driven sleeve 26, but is spaced therefrom far enough to accommodate the piston retracting spring 33. A washer 35 supports the driving sleeve 25 below the gear 29 thereon and is held 25 against an annular shoulder 36 provided therefor in the vertical housing bore by means of the spring 33. The piston is provided below the bottom or lower portion of the driven sleeve 26 with an annular groove 37 and terminates below said 30 groove in a flatsided head portion 38. The lower end of the piston retracting spring 33 is supported upon an annular seat provided therefor on a member 39 having a lateral notch 40 therein whose upper portion snugly receives the grooved 35 portion 37 of the piston and whose lower portion is widened to receive the head 38 at the lower end of said piston. Thus, the spring seat member 39 is held against axial movement relative to the piston, but may be rotated relative thereto and removed sidewise therefrom.

40 The bottom wall of the lower or driven sleeve 26 on each piston fits between the upper end of the spring seat member 39 thereon and a collar 41 formed integral therewith, thereby preventing 45 relative axial movement of said sleeve and said piston. The tappet cup 3 is adjusted vertically by means of a block 42, which is slidably supported in an undercut cross slideway 43 provided therefor in the bottom of the spring seat member 39. The 50 adjusting block is inserted in and removed from the slideway 43 in the spring seat 39 through an opening 44 provided therefor in the side wall of the tappet cup 3, said block being provided with a threaded bore 45 adapted to be engaged by a 55 threaded pin (not shown) for inserting and removing it through said opening. As shown in Fig. 4, the adjusting block has a raised middle portion 42a that fits within the lower end of the spring 33, thereby retaining said block in the 60 slideway 43 provided therefor in the spring seat 39.

65 As shown in the drawings, the rack or control rod 27 has a loose fit in the longitudinal bore 28 provided therefor in the pump housing and extends beyond the ends of said housing. The forward end 46 of the rack rod is adapted for connection with a suitable mechanism (not shown) for reciprocating the rod in the housing, no fuel being delivered by the pump when said rod is at 70 one end of its reciprocating movement and a maximum quantity of fuel being delivered when said rod is at the other end of said movement. The rack rod is slidably supported in the forward end of the housing bore 28 by means of a bushing 28a threaded therein. A cylindrical casing 47 has

5 a reduced end portion 48, which is threaded into the other end of said bore and slidably supports said rack rod. This cylindrical casing contains and forms part of a device that limits the rearward travel of the rack rod and thus controls the maximum quantity of fuel delivered by the pump.

10 Mounted in the casing 47 for longitudinal sliding but non-rotary movement therein is a stop bar 49 that is disposed crosswise of said casing with its ends supported in diametrically opposed longitudinal slots 50 cut in the cylindrical wall thereof. The stop bar or member 49 is adapted to be directly engaged by the adjacent end of the rack rod 27 or by a plug 51 that seats within an axial recess provided therefor in said end of said 15 rack rod. The ends of said stop bar are provided with threads adapted to cooperate with the internal thread of an externally knurled sleeve 52 that is rotatably mounted on the cylindrical casing 47 of the rack rod stop device between the 20 adjacent end wall of the pump housing and an annular shoulder formed on said casing adjacent to the outer end thereof, which is shaped to receive a wrench. By this arrangement, the stop bar 49 may be adjusted longitudinally of the casing 47 to vary the rearward travel of the rack rod and thus regulate the maximum quantity of fuel delivered by rotating the knurled sleeve 52 which, due to its threaded connection with said stop bar, causes the latter to move longitudinally of the 25 guide slots 50 provided therefor in said casing. The adjusting sleeve 52 may be locked in the desired position of its rotary adjustment by means of a cotter pin 53 that extends through registering openings provided therefor in the outer end 30 portion of the sleeve and the removable casing or holder.

35 The rack rod is provided with a series of longitudinal detachable rack sections or blocks 54 adapted to intermesh with the gears 29 of the respective metering or driving sleeves 25. Each of the rack sections 54 is slidably mounted in a longitudinal slideway 55 provided therefor in the cylinder opposing side of the rack rod, said slot being undercut and said rack sections having top 40 and bottom ribs or flanges 56 that fit the undercut portions of said slot to prevent sidewise removal of said sections from said rod. Each of the rack sections 54 is adjusted longitudinally of the rack rod and is locked in adjustment position 45 preferably by means of two horizontally spaced parallel screws 57 that are threaded into said rod transversely thereof and have conical end portions 58 adapted to engage horizontally spaced conical recesses 59 provided therefor in the rack rod of 50 said rack section. The space between the two screws 57 is less than the space between the two recesses 59 engaged thereby, whereby the rack section is shifted longitudinally of the rack rod when one of said screws is tightened and is shifted 55 in the opposite direction when the other screw is tightened. When one of the screws is tightened, the other is loosened to permit the sliding movement imparted to the rack section by the first mentioned screw; and when both screws are 60 tightened, the rack section is locked to the rack rod. The rear wall of the pump housing 1 is provided opposite the outer or rear ends of each pair of adjusting screws 57 with an opening 60 through which a suitable tool may be inserted to turn said 65 screws, said opening being closed by means of a threaded plug 61. The teeth of the endmost rack sections terminate short of the outer ends thereof, leaving plain end portions that are long 70 enough to prevent the endmost gears from running

ning out of mesh with said rack teeth, thereby limiting endwise movement of the rack rod in both directions.

The hereinbefore described piston rotating mechanism has numerous advantages. The toothed rack rod sections may be quickly and easily removed and replaced when worn or damaged; and said sections may be adjusted longitudinally of the rack rod independently of each other to obtain a uniform angular adjustment of all of the pump pistons without removing the rack bar or dismantling the pump. The stop mechanism for the rack rod is of simple, economical and compact construction; it may be quickly and easily adjusted to control the maximum quantity of fuel delivered and locked in the desired position of adjustment; and it is also adapted to be mounted on and dismounted from the pump housing as a complete unit.

20 The above described tappet adjusting mechanism is not claimed herein, being the subject matter of a separate application Serial No. 70,805, filed concurrently with this application.

What I claim is:

25 1. A fuel injection pump comprising a housing, a piston reciprocable therein, and means for turning said piston on its axis to vary its angular position, said means comprising a member slid- 30 able in said housing transversely of the piston axis, a rack removably mounted on said member and operatively connected to said piston to turn the same, and means for adjusting said rack relative to said member in the direction of the sliding movement thereof and for locking said rack 35 to said member in the desired adjusted position, said last mentioned means comprising two screws threaded into said member and spaced apart in the direction of its sliding movement and having tapered ends adapted to engage tapered recesses 40 provided therefor in said rack, the spacing of said screws differing from the spacing of said recesses.

2. A fuel injection pump comprising a housing, a piston reciprocable therein, and means for turning said piston on its axis to vary its angular position, said means comprising a member slid- 45 able in said housing transversely of the piston axis, a rack removably mounted on said member for sliding movement longitudinally thereof and operatively connected to said piston to turn the same, and means for adjusting said rack relative to said member in the direction of the sliding movement thereof and for locking said rack to said member in the desired adjusted position, said last mentioned means comprising two screws threaded into said member and spaced apart in the direction of its sliding movement and having tapered ends adapted to engage tapered recesses provided therefor in said rack, the spacing 50 of said screws differing from the spacing of said recesses, said housing being provided with an opening through which access may be had to said screws, and a removable closure for said opening.

3. A fuel injection pump comprising a housing, 60 a plurality of pistons reciprocable therein, and means for turning said pistons on their axes to vary the angular position thereof, said means comprising a rod axially slid- 65 able in said housing transversely of the piston axes, longitudinally spaced separate rack sections removably mount-

ed on said rod and operatively connected to the respective pistons to turn the same, and means for independently adjusting each of said rack sections longitudinally of said rod and for locking said rack section in the desired adjusted position, said last mentioned means comprising two screws threaded into said rod and spaced apart longitudinally thereof and having conical ends adapted to engage conical recesses provided therefor in said rack sections, the spacing of said screws differing from the spacing of said recesses.

4. A fuel injection pump comprising a housing, a plurality of pistons reciprocable therein, and means for turning said pistons on their axes to vary the angular position thereof, said means comprising a rod axially slidable in said housing transversely of the piston axes and provided with a longitudinal undercut slide way, and separate rack sections slidably mounted in said slide way and operatively connected to the respective pistons to turn the same, and means for independently adjusting each of said rack sections longitudinally of said slide way and for locking said rack section in the desired adjusted position, said last mentioned means comprising two screws threaded into said rod through the bottom of said slide way and spaced apart longitudinally thereof and having conical ends adapted to engage conical recesses provided therefor in the slide way bottom opposing face of said rack section, the spacing of said screws differing from the spacing of said recesses.

5. A fuel injection pump comprising a housing, a plurality of pistons reciprocable therein, and means for turning said pistons on their axes to vary the angular position thereof, said means comprising a rod axially slidable in said housing transversely of the piston axes, and separate rack sections removably mounted on said rod and operatively connected to the respective pistons to turn the same, and means for independently adjusting each of said rack sections longitudinally of said rod and for locking said rack section in the desired adjusted position, said last mentioned means comprising two screws threaded into said rod and spaced apart longitudinally thereof and having conical ends adapted to engage conical recesses provided therefor in said rack section, the spacing of said screws differing from the spacing of said recesses, said housing being provided with openings through which access may be had to said screws, and removable closures for said openings.

6. A rack rod for angularly adjusting the pistons of a multicylinder fuel injection pump comprising a rod provided with a longitudinal undercut slide way, a plurality of longitudinally spaced rack sections slidably mounted in said slide way, and means for independently adjusting each of said rack sections longitudinally of said slide way and for locking said rack section in the desired adjusted position, said adjusting and locking means comprising two screws threaded into said rod through the bottom of said slide way and spaced apart longitudinally thereof and having conical ends adapted to engage conical recesses provided therefor in the opposing face of said rack section, the spacing of said screws differing from the spacing of said recesses.
